UNITED STATES PATENT OFFICE.

CLEMENT A. DUNBAR, OF DETROIT, MICHIGAN.

GLASS-BLOWER'S MACHINE.

SPECIFICATION forming part of Letters Patent No. 657,097, dated September 4, 1900.

Application filed March 5, 1900. Serial No. 7,383. (No model.)

To all whom it may concern:

Be it known that I, CLEMENT A. DUNBAR, a citizen of the United States, residing at Detroit, in the county of Wayne and State 5 of Michigan, have invented certain new and useful Improvements in Glass-Blowers' Machines, of which the following is a specification, reference being had therein to the accompanying drawings.

10 The invention consists in the construction of a glass-blower's machine, and particularly in the construction of a machine comprising a movable mold which is closed at the blowing-point and is then moved away from the blowing-point and opened, the opening being effected in such a way as to prevent the possibility of injuring the blown article.

15 The invention further consists in the construction of the various parts, as more fully 20 hereinafter described and then specifically pointed out in the claims.

In the drawings, Figure 1 is a plan view of my machine. Fig. 2 is a vertical central section thereof on line xx , showing at the right 25 hand in dotted lines the blowpipe, with the gather thereon, when inserted in position in the mold and at the left hand a finished bottle standing in the opened mold. Fig. 3 is a section on line yy , Fig. 1, illustrating the 30 construction of the mechanism for closing the mold. Fig. 4 is a perspective illustrating the holding device for one section of the mold at the blowing-point. Fig. 5 is a vertical section showing that holding device in connection 35 with the connections to the mold-section. Fig. 6 is a perspective view of one of the molds and portion of the camway which actuates one of the mold-sections, showing that mold-section lifted to clear the blown article. 40 Fig. 7 is a vertical section through the mold, the section L' thereof being slightly raised.

45 My invention is particularly intended as an assistance to the glass-blower. It is intended to be operated either by the glass-blowers themselves or by an attendant, or both, and to provide mechanical means to open the mold-sections perfectly without danger of damage to the blown article, thus obviating the use of the boy ordinarily employed by the glass-blowers to open the mold. 50 It is well known that boys, even though experienced in this work, destroy a large per-

cent. of the blown articles, and thus reduce the output of the blower, to say nothing of the expense of employing such boys and the 55 uncertainty of their being on hand when wanted. The machine also is intended to enable the blowers to operate more rapidly, and thus in a given time to turn out more finished product than by the old device. 60

A is the base of the machine, B being the top thereof, which is stationary. Above the top is a mold-carrier C, shown in the form of a table turning upon the central pivot D. This pivot has at its lower end a bevel-pinion 65 E, meshing with the bevel gear-wheel F upon the shaft G, journaled in horizontal bearings in the base. On the shaft G is a ratchet-wheel H, which is shown in Fig. 2 by breaking away part of the gear-wheel F. 70

I is a lever on the shaft G and having a pawl J engaging with the ratchet-wheel. K is a second lever journaled in the base, having the bearings aa above the lever I and arranged so as to successively impinge upon the 75 lever I as the lever K is moved downward. By depressing the lever K the operator through the mechanism described will impart to the mold carrier or table C a rotational movement. The amount of this rotational 80 movement may be determined by the relative size of the wheels E and F. In this case I have shown the movement at each operation as one-quarter of a revolution of the table C. That is not essential, as for different classes 85 of work different gear-wheels may be used and the table given either an entire revolution or such fractional part thereof as is desired. In case, for instance, I use but one mold on a table it would travel the entire 90 distance around the circle. If I used two molds, it would move a half-circle, and if I used three molds it would move the third of a circle, and so far as a certain feature of my 95 invention is concerned—that is, for opening and closing the mold in the desired manner—it is immaterial what movement is given to the carriage at each operation. The ordinary form, however, will be that shown in the drawings, in which it takes four operations of the lever K to make a complete rotation of the mold-carrier.

100 My machine is intended to be used in connection with the ordinary molds which every

glass-factory has in use, so that manufacture of special molds will not be required, and I have therefore shown an ordinary two-section mold comprising the sections L and L', pivoted upon the pins M, which are fixed to the table or to a base (not shown) which might be fixed to the table. Between these sections and in the proper relation thereto is secured to the table the bottom plate O. I have shown it secured by means of a set-screw c, passing through the table. This bottom plate may be made an integral part of the table C, or in case where ordinary molds with a base-plate are used it may be attached thereon in the usual manner. The molds have the usual opening for the handles, and in the mold-section L' may be secured the usual handle P, while in the mold-section L I secure an eyebolt or block Q'. To the handle P is attached a block Q, preferably by making a sleeve thereon through which the handle passes and locking the block to the handle in any suitable manner, as by a set-screw d. This block has a vertical aperture, through which passes a vertical stem e at its lower end, carrying a grooved roller h, riding on a camway R. A set-screw i adjustably secures together the block and the stem e.

30 k is a curved friction-shoe upon the block Q. This friction-shoe is adapted to bear against a holding device (shown in Fig. 4) consisting of a roller l, sleeved on the arm m of a bell-crank lever pivoted on the pin n, the other arm o of which has a counterweight p thereon.

q shows friction-rollers of larger diameter than the roller l and at opposite ends thereof and bearing against the vertical plate r, to which the pivot-pin n is secured.

The eyebolt Q' engages with the vertical pin S on the end of the mold-actuating arm S', forming an adjustable pivotal connection between these parts, which arm extends across the table C and is connected to a sliding block s. This connection I preferably make adjustable by means of a stem s', engaging an aperture in the end of the arm S' and held by means of a set-screw t. The block s has a headed pin u passing through a longitudinal slot in the table.

T is a slide working in suitable guides upon the upper face of the top B of the base and having a lug or projection w near its end extending up behind the lower end of the pin u. This slide T may be actuated in any suitable manner—as, for instance, by the bell-crank lever T', connected thereto, which in turn is actuated by the foot-rod T², extending up in the position for the operator to place his foot upon the top. It is evident that if the operator places his foot upon the foot-rod T² he will through the connections described move the arm S' and with it the mold-section L to its closed position. The camway R preferably extends entirely around the table and is of a shape to be hereinafter

described for the purpose of opening and closing the mold-section L'.

While I have described but one mold and 70 the connections thereto, it will be understood that each mold has a similar connection and attachments and that each will be operated as follows: The foot-rod T² is located at the point where the blower stands. This is represented in Figs. 1 and 2 of the drawings as at the right hand thereof. In this position the mold-section L' at the blowing-point is held in its closed position by the wedging of the roller l between the shoe k and the plate 80 r, thus holding one mold-section stationary in its closed position, so that the operator may rest his blowpipe against it and center the gather therein. As soon as the gather is in position the operator presses down upon 85 the foot-rod T² and through the connections described pushes in the arm S' and closes the mold-section L. He then blows the bottle in the ordinary manner and breaks away the blowpipe above the top of the mold, leaving 90 the blown article within the closed mold. The operator or boy who is upon the opposite side of the machine for the purpose of carrying away the bottles or handing them to the carrier depresses the lever K, and thus through 95 the connections previously described rotates the table one-quarter turn, the mold moving from the blowing position to the position numbered 2 at the top of Fig. 1, the mold-section still remaining closed, and another mold moving from the position numbered 4 is moved into the blowing position ready for the same or another blower to blow a bottle therein. The mold at the position numbered 2 will thus remain during the blowing of the next 100 bottle and for sufficient time to cool if that time is necessary, as is required in certain classes of work. The downward movement of the lever K rocks the lever I, and the lever I has connected to it a rock-arm U, which is connected to a rock-arm U' by connecting rod U², the rock-arm U' being on a shaft V, to which is connected the bell-crank lever T'. Thus the downward movement of the lever K will raise the foot-rod T² to its original position 115 and return the slide T, ready for another operation. It is obvious that as this has a rigid connection the subsequent movement of the foot-rod T² will raise the lever K to its initial position. After the mold has remained at the 120 position numbered 2 during the blowing of the next article the next operation of the lever K moves it from that position to the position numbered 3, and in traveling from the position 2 to the position 3 the mold will be 125 opened. As the mold leaves the position 2 the first operation of opening is to slightly lift the mold-section L', so as to free it from the shoulder of the bottle, and then very slightly open it. The lifting operation is effected by the running up of the roller h upon the cam v on the camway R, which is shown in Fig. 6, that figure illustrating the section L' of the mold in its slightly-raised position.

The camway then gradually extends outward from the table C, so that the further travel of the roller h thereon will gradually open the section L'. At the same time that the 5 section L' is opening the section L is also opened, but the section L does not commence to open until the section L' has first been lifted, as described, and opened sufficiently to allow a film of air to pass around the bottom upon one side and stiffen the glass by chilling it and also to admit the air gradually, so that the opening of the mold will not produce sufficient suction to draw out or bulge the plastic bottle. The section L is opened 10 by the engagement of the head of the pin u with the cam w during the travel of the mold from the position 2 to the position 3. This cam is shown in dotted lines in Fig. 1 and is shown in elevation at the right hand of Fig. 15 2, being formed upon or attached to the stationary table or top B. When the mold reaches the position 3, it is opened wide enough to permit the withdrawal of the blown article, and all that is required in the further 20 movement from position 3 to the blowing position is that the section L' shall be moved by the camway R to the closed position previously described. In order to stop the machine at the proper point, I have a series of 25 pins x, Figs. 1 and 3, which are adapted to strike against the end of the slide T when that slide is in its innermost position, and thus stop the table at the proper point. It is evident that as soon as the slide T is moved 30 longitudinally when the operator presses down upon the rod T² the slide will be withdrawn from the path of the pin x and the table be then moved to the next position.

I preferably apply a brake to the table to 35 prevent any rebound or backward movement. This may be of any suitable form. I have shown the friction-roller V' journaled in the slide V² upon the slide T and held in frictional engagement in the inner position of 40 the slide T by means of the spring V³. Any other form of brake may be employed for this purpose.

By arranging the pin S in the end of the arm S' of some considerable length I am enabled 45 to use molds of different sizes upon the same machine. Vertical adjustment is also provided between the handle P and the roller h by the adjustable engagement of the stem e in the block Q, and longitudinal adjustment 50 between that block and the mold-section L' is provided by means of the set-screw d.

What I claim as my invention is—

1. An operating device for glass-blowers' 55 molds comprising in combination with a carrier, and a multiple of molds thereon, of means by which the operator may close the mold at the blowing-point, and mechanism by which an operator may move the carrier and thereby open a mold containing a blown 60 article.

2. An operating device for glass-blowers' 65 molds comprising in combination with an endless carrier, and a mold thereon, of means by which the operator may close the mold at the blowing-point, and mechanism by which an operator may actuate the carrier to move the filled mold away from the blower and for 70 opening the mold during such movement.

3. In a glass-blower's machine, a traveling 75 sectional mold, means for actuating one section of the mold from its open to its closed position, in moving to the blowing-point, and separate, operator-controlled means for closing the other section.

4. In a glass-blower's machine, means for 80 raising a mold-section, and means for separating the sections after such raising.

5. In a glass-blower's machine, means for 85 performing the following operations successively for raising a mold-section, then slightly opening the same so as to admit a film of air around the article on one side, and then to gradually open the mold.

6. In a glass-blower's machine, means for 90 raising one section of a sectional mold, means for slightly opening the same, and means for then gradually opening both mold-sections.

7. In a glass-blower's machine, a traveling 95 sectional mold, means operating during the travel to vertically separate the mold and article, and then to gradually open the mold-sections.

8. In a glass-blower's machine, a traveling 100 sectional mold, means operating during the travel of the mold to first separate a mold-section from the article by a vertical movement, means for then slightly opening the said section, and means for then opening the mold gradually, to its "open" position. 105

9. In a glass-blower's machine, a movable 110 mold-carrier, a mold thereon having movable mold-sections, means for opening both sections and for closing one section during the travel of the mold, and means under the control of the operator for closing the other section at the "blowing-point."

10. In a glass-blower's machine, a sectional 115 mold movable to and from the blowing-point, means for actuating one mold-section to its closed position in moving to the blowing-point, the other mold-section being free, and operator-controlled devices for closing said free section.

11. In a glass-blower's machine, a mold- 120 carrier, a sectional mold thereon, a stationary cam means connecting a mold-section therewith, such connection comprising a vertical and horizontal adjustment.

12. In a glass-blower's machine, a mold-carrier, a sectional mold thereon, a cam adjacent to the carrier, a connection between the mold-section and cam comprising the block Q connected to the mold-section, the roller h connected to the block Q and engag- 125 130

ing the cam, the inclined head *k* on the block *Q*, the counterweighted roller adapted to be struck by the head *k*, and the plate *r* over which said roller travels for the purpose described.

13. In a glass blower's machine, a movable mold-carrier, a multiple of molds thereon, an arm connected to each mold through which it may be closed, and a common mechanism controlled by the blower into operative relation with which the arm of each mold comes successively.

14. In a glass-blower's machine, a mold-carrier, the molds thereon, an actuating device for the carrier, a mold-closing device, and connections between the two whereby they are required to be successively operated and whereby the operation of one resets the other.

15. In a glass-blower's machine, a rotating mold-carrier, sectional molds thereon, the cam around the carrier, a connection from the outer mold-section to said cam, said cam being shaped to first open, and then to close said mold-section, in the revolution of the carrier, an operating connection to the inner mold-section, for opening said section in the revolution of the carrier, and means by which the operator may close the inner section at the blowing-point.

16. In a glass-blower's machine, a movable mold-table, sectional molds thereon, means by which the operator may move it through fractional parts of a revolution, means for holding the mold closed during the first operation, and for opening the mold, having the blown article therein, during the succeeding operation, said means comprising devices for first separating the article and mold vertically, then opening the mold-sections successively.

17. In a glass-blower's machine, a movable sectional mold, successively-operating mechanism for first opening both sections, for next closing one section during the movement of

the mold and means by which the operator may subsequently close the mold.

18. In a glass-blower's machine, a sectional mold, mechanism for positively opening and closing one section of the mold and mechanism for opening the other section simultaneously with the opening of the first section during the movement thereof, and independent means under the control of the operator for closing said second section after the first section is closed.

19. In a glass-blower's machine, a sectional mold, means for opening the same comprising devices for initially opening one section to admit a thin film of air around one side of the article, and devices for thereafter opening the mold to permit the article to be withdrawn.

20. In a glass-blower's machine a sectional mold, means by which the operator can move the mold away from the blowing-point to the opposite side of the machine where the article may be removed, means for opening the mold during such movement, means at the "taking-out" point by which the operator may return the mold to the blowing-point, devices for closing one section during such movement, and devices by which the "blower" can close the other section.

21. In a glass-blower's machine, a sectional mold, operating-cams for actuating the mold-sections, connecting means between the cams and mold-sections comprising a vertical and horizontal adjustment.

22. In a glass-blower's machine, a sectional mold, its handles, such as *P*, of a bracket adjustable longitudinally thereon, and an actuating-cam connection with such bracket comprising a vertical adjustment.

In testimony whereof I affix my signature in presence of two witnesses.
